UNITED STATES PATENT OFFICE.

CHARLIE RUFUS REID AND CECIL FELIX HEIDELBERG, OF HEIDELBERG,
MISSISSIPPI.

STORE-BIN.

SPECIFICATION forming part of Letters Patent No. 738,572, dated September 8, 1903.

Application filed October 4, 1902. Serial No. 125,986. (No model.)

To all whom it may concern:

Be it known that we, CHARLES RUFUS REID and CECIL FELIX HEIDELBERG, citizens of the United States, residing at Heidelberg, in the 5 county of Jasper and State of Mississippi, have invented a new and useful Store-Bin, of which the following is a specification.

The invention relates to store-bins adapted for nails or other commodities; and the object 10 in view is to provide a simple, inexpensive, and efficient device of this class adapted for arrangement beneath the counter and accessible either at the front or rear thereof or for use independently of a counter, as at an intermediate point on the store-floor, and, furthermore, to provide a device of this class adapted 15 particularly for containing articles which do not readily seek their level in the bin and of which the weight must be equalized in returning the bin to its normal position in order that it may remain upright.

Further objects and advantages of this invention will appear in the following description and the novel features thereof will be particularly pointed out in the appended claims, 25 it being understood that various changes in the form, proportion, and the minor details of construction may be resorted to without departing from the spirit or sacrificing any of 30 the advantages of this invention.

In the drawings, Figure 1 is a perspective view of a bin constructed in accordance with the invention. Fig. 2 is a longitudinal sectional view of the same. Fig. 3 is a vertical 35 section taken on line 3 3 of Fig. 2.

Similar reference characters indicate corresponding parts in all the figures of the drawings.

In the illustrated embodiment of the invention 40 the bin consists of a plurality of pivoted tilting receptacles 1, supported by a portable frame consisting of longitudinal parallel bars 2, secured together at their extremities by transverse sills 3, which extend beyond the 45 outer surfaces of the side bars to form feet, and uprights or standards 4, secured at their lower ends between and properly spacing the side bars at their extremities and at intermediate points and also serving to space the 50 receptacles 1, the lower ends of the uprights being flush with the lower edges of the side

bars and adapted to rest on the supporting-surface, said uprights supporting the weight of the bins and their contents, and thus permitting the side and end bars to be made 55 of very light material to render the device lighter and adapt it to be more easily moved. The receptacles are tapered toward their bottoms and have parallel side walls having bearing-openings, into which project pivot-pins 60 6, supported by the standards, said bearings being located midway between the obliquely-disposed end walls of the receptacles and above the mid-depth of the receptacles to support in stable equilibrium. The receptacles 65 may be separately tilted in either direction—namely, forwardly or rearwardly—and the interval between the pivot-pins and the upper edges of the side bars of the frame is such as to permit each receptacle to be reversed 70 in position with its top or open side downward, whereby accumulations of dust or other foreign matter therein may be readily emptied without altering the position of the frame. Moreover, as each receptacle is mounted for 75 a free swinging movement the contents thereof, such as nails or other articles which do not readily find their level, may be distributed so that the receptacle may normally occupy 80 a vertical position by shaking the receptacle 80 as it is returned to its normal position after the discharge of a portion of its contents for the purpose of sale or otherwise.

Having described the invention, what is claimed is—

1. A store-bin having a frame consisting of a base and spaced uprights, downwardly-tapered receptacles arranged between the uprights and having bearing-openings in the side walls thereof at points above their mid-depths, pins extending transversely through the uprights and projecting into the bearing-openings in said receptacles, the pin of an intermediate upright having its terminals extended laterally on either side of the upright 90 and projecting into the bearing-openings in the side walls of adjacent receptacles, one pin 95 operating as a trunnion for supporting one side of two receptacles.

2. A store-bin comprising a frame having 100 parallel side bars, terminal transverse sills connecting the side bars and extending beyond the

planes thereof to form feet, spaced uprights arranged between and in contact with the side bars and secured thereto, the lower ends of the uprights being flush with the lower edges of the side bars, pins carried by the uprights, and downwardly-tapered receptacles arranged between the uprights and having bearing-openings in the side walls thereof at points above their mid-depths into which the pins carried by the uprights are adapted to extend, said pivot-pins being disposed at an elevation

above said side bars sufficient to allow reversal of the receptacle.

In testimony that we claim the foregoing as our own we have hereto affixed our signatures ¹⁵ in the presence of two witnesses.

CHARLIE RUFUS REID.
CECIL FELIX HEIDELBERG.
